(57) **CLAIM**

The ornamental design for an aquarium water heater, as
shown and described.

DESCRIPTION

FIG. 1 is a front elevational view of a first embodiment of
the aquarium water heater in which an optional strainer is
illustrated as being attached to the bottom portion thereof, in
accordance with my new design;

FIG. 2 is a rear elevational view thereof;

FIG. 3 is a left side elevational view thereof, the right side
elevational view thereof being a mirror image of the left
side;

FIG. 4 is a top plan view thereof oriented such that the rear
of the aquarium water heater is at the bottom of the sheet;
FIG. 5 is a bottom plan view thereof oriented such that the
rear of the aquarium water heater is at the bottom of the
sheet;

FIG. 6 is a right side, front isometric view looking somewhat
downwardly on a second embodiment of the aquarium water
heater in accordance with my new design, wherein the
optional strainer is absent from the bottom portion of the
aquarium water heater;

FIG. 7 is a top plan view of the second embodiment oriented
such that the aquarium water heater is at the bottom of the
sheet; and,

FIG. 8 is a bottom plan view of the second embodiment oriented
such that the rear of the aquarium water heater is at the
bottom of the sheet.

The left side elevational view of the second embodiment of
the aquarium water heater is the mirror image of that shown
in the isometric view of FIG. 6, and the rear elevational view
thereof is as shown in FIG. 2 of the first embodiment, but
without the optional strainer that is attached to the bottom of
FIG. 2.
